SANITARY CAN OPENER APPARATUS

Roy A. Bruce and Robert W. Haman, Elmhurst, Ill., assignors to The Wander Company, Chicago, Ill., a corporation of Delaware

Application September 16, 1949, Serial No. 116,088

7 Claims. (Cl. 30—4)

1

The present invention relates generally to improved apparatus for effecting automatic and sanitary opening of sealed containers, and is particularly adapted for use in opening metal cans containing beverages which are frequently dispensed by conventional type automatic vending machines.

The packaging of foods in individual containers for merchandising in automatic vending machine has long been commonplace. Moreover, it is well known that the bulk of the merchandise delivered by automatic vending machines is normally consumed in the immediate vicinity of the machine, and this is particularly true in the case of beverages. Accordingly, the provision of suitable means for accomplishing immediate and safe opening of the purchased containers is considered to be essential to successful vending of such merchandise.

In the use of container and can opening means known prior to the present invention, there has been a tendency for a portion of the contents to adhere to or accumulate upon certain operative elements of the opening device. Such accumulations are always unsightly, and in merchandising foods which contain a substantial percentage of protein and fat, such as chocolate milk, etc., the adhering material constitutes a favorable medium for bacteria growth resulting in somewhat unsanitary operation.

It is therefore an object of the invention to provide improved, container-opening apparatus which is operative to open most containers of the can type, which is adapted for clean and sanitary operation in repeated use, and which may be used in combination with a vending machine or placed, independently, on a store counter near the point of sale of sealed cans or other containers.

A specific object of the invention is to provide a novel sterilizing arrangement for accomplishing thorough asepticizing of a punching or piercing member in automatic can opening apparatus. Other objects and advantages of the invention will become apparent by reference to the following specification and accompanying drawings, wherein selective embodiments of the novel structure are illustrated.

In the drawings:

Fig. 1 is a perspective view of a conventional type vending machine incorporating the novel container-opening device of the invention;

Fig. 2 is an enlarged front view of the container-opener device;

Fig. 3 is a fragmentary view taken along the lines 3—3 in Fig. 2;

2

Fig. 4 is a perspective view of a can which contains a solution for asepticizing the punching or piercing member used in opening a can of merchandise;

5 Figs. 5 and 6 are side views, partially in section, of the can shown in the previous figure;

Fig. 6a is a perspective view of a member disposed within the can of asepticizing solution;

Fig. 7 is a view taken along line 7—7 in Fig. 6;

10 Figs. 8 and 9 are side views, partially in section, of a can containing an asepticizing solution showing successive positions of a punching member within the can;

15 Fig. 10 is a sectional view taken substantially along lines 10—10 in Fig. 2;

Fig. 11 is an enlarged view of a portion of the structure shown in Fig. 2, certain portions being broken away to more clearly show parts of the operating mechanism for the can opening apparatus;

20 Fig. 12 is a plan view of the operating mechanism illustrated in Figs. 10 and 11;

Fig. 13 is a schematic illustration of the control circuit and operating mechanism;

25 Fig. 14 is a diagram showing the speed of the motor actuating the can opening mechanism at various times during operation;

Fig. 15 is another diagram indicating successive positions of the punching member during operation; and

30 Figs. 16 and 17 illustrate a modification embodying certain features of the invention.

Can opening apparatus in accordance with the invention may comprise a separate unit which can be placed upon a counter or table and used to open cans or the like independently of other apparatus. However, for purposes of describing the invention, the can opening apparatus, indicated generally at 13 in the drawings, is shown incorporated in a conventional type vending machine, designated 15.

40 The vending machine 15 comprises a cabinet 16 of conventional construction which contains and supports the various operative elements of the machine and provides a pleasing outward appearance. The elements of the machine comprise, in the present instance, means (not shown) for storing sealed cans of merchandise, as for example, chocolate milk, a disbursing tray 17, the can opening apparatus 13, and a coin operated unit 19 which is operative to drop a single can of chocolate milk from the storage means (not shown) into the disbursing tray 17 and to ready the can opening apparatus 13 for operation.

45 50 55 The vending machine 15 comprises a cabinet 16 of conventional construction which contains and supports the various operative elements of the machine and provides a pleasing outward appearance. The elements of the machine comprise, in the present instance, means (not shown) for storing sealed cans of merchandise, as for example, chocolate milk, a disbursing tray 17, the can opening apparatus 13, and a coin operated unit 19 which is operative to drop a single can of chocolate milk from the storage means (not shown) into the disbursing tray 17 and to ready the can opening apparatus 13 for operation.

For operation of the machine 15, a coin or token is dropped into a slot 23 in the coin operated unit

19 whereupon a can 25 of chocolate milk drops into the disbursing tray 17. The can 25 is then removed by the purchaser and placed into the can opening apparatus 13 which is operable to pierce or puncture the can. The can 25 may then be removed from the apparatus 13 and the contents consumed. If the vending machine 15 is empty, this condition is signified by illumination of a light 27 on the face of the machine 15. A coin return receptacle 28 is provided in the coin operated unit 19 for returning the deposited coin or token if the supply of cans is exhausted, or if the coin is defective.

The can opening apparatus 13 includes a housing 29, punching or piercing means 31 for opening the can 25, power means 33, power transmission means 35 for connecting the power means 33 to the punching means 31, means 36 for asepticizing the punching means 31 so as to provide sanitary operation, and a control circuit or timing means 37 for actuating the power means 33 in proper sequence. In the illustrated embodiment, the can opening apparatus 13 also includes means 39 for storing straws 41 which may be used by the purchaser in consuming the contents of the can 25. The straw storage means 39 is located in the housing 29 so that the straws are readily available.

In operation, the punching means 31 is moved from a standby or rest position, shown at 43 in Figs. 2 and 3, into contact with the can 25 to pierce the can. After the can 25 is opened, the punching means 31 is withdrawn from the can and is moved past its rest position 43 into the asepticizing means 36 which washes off and/or kills any harmful bacteria on the operative portion of the punching means. The punching means 31 is then automatically returned to the rest or standby position 43 and is ready for further operation.

The housing 29 of the apparatus 13 is generally box-shaped (Fig. 2) and is fabricated from suitable angle and plate members. In the illustrated construction, the housing 29 is supported upon the main frame structure (not shown) of the vending machine 15 and the interior of the housing 29 is made accessible for maintenance and other purposes through the provision of a removable back plate 47 which is screwed to the housing 29 as shown at 49 (Fig. 10).

Openings 51 and 53 are formed in the face of the housing 29 (Fig. 2) to permit insertion and removal of the cans 25 of chocolate milk and access to the asepticizing means 36, respectively. These openings 51 and 53 are closed by doors 55 and 57 which slide vertically in tracks (not shown) attached to the housing 29. For convenience in raising and lowering the doors 55 and 57, knobs 56 and 58 are provided. It will be understood that the doors may be hingedly or otherwise supported. The door 57 is normally locked in the closed position by a manually operated latch 58a which is pivotally supported upon the housing 29 (Fig. 3).

The housing 29 is separated into compartments, 59 designating a chamber for the can 25 of merchandise, 61 indicating a chamber for the asepticizing means 36, and 63 designating a compartment in which the timing means 37, power means 33, and power transmission means 35 are located. A casing 64 having back member 65 is disposed within the housing 29 and separates the compartment 63 located in the rearward portion of the housing 29, from the chambers 59 and 61. A vertically disposed plate 67 (Fig. 11) extends between the back member 65 of the casing 64 and a portion of the housing 29 disposed between the

openings 51 and 53 to provide the chambers 59 and 61.

Each of the chambers 59 and 61 includes a suitable guide means 71 disposed therein for holding the can 25 and the asepticizing means 36 in a predetermined position, in order to positively locate these elements for engagement by the punching means 31. In the illustrated construction, the guide means 71 includes a plurality of vertically extending rods 73 which are fixedly attached to the housing 29 at their lower ends and to a semi-circular rim 75 at their upper ends. The rim 75 is adapted to fit over the top of the can 25 and asepticizing means 36 (Figs. 3 and 10).

The straw containing means 39 is attached to the casing 64, as shown in Fig. 2, and includes a cylindrically shaped can 77 which is accessible through an opening 79 in the face of the housing 29. The opening is closed by a circular door 81 which may be opened by a knob or tab 83 attached to the door.

The punching means 31 moves alternately between compartments 59 and 61 during operation and includes a spike or bit 85 which is preferably fabricated from a stainless, corrosion resistant alloy. The bit 85 is threadedly attached to a collar 87 at its upper end, the collar being connected to the power transmission means 35 by a rod 89 which extends through an arcuate slot 90 formed in the back plate 65 of the casing 64 (Figs. 10 and 11).

The power transmission means 35 is operative to move bit 85 alternately into the can 25 and into the asepticizing means 36 by movement of the connecting rod 89 along the arcuate slot 90. The power transmission means 35 is further adapted to maintain the bit 85 in a vertical position at all times (Fig. 10). In order to move and position the bit 85 in the desired manner, the power transmission means 35 includes a drive gear 93 which simultaneously meshes with a pair of vertically aligned spur gears, one spur gear 95 being disposed above and the other spur gear 97 being located below the drive gear 93.

The gears 95 and 97 are keyed to shafts 99 and 101, respectively, by pins 103 and 105. The shafts are journalled in suitable bearings 106 which are supported upon a vertically extending angle shaped structural member 108 the lower end of which is attached to the housing 29. The drive gear 93 is keyed to a shaft 107 by pin 109, the shaft being operatively connected to power means 33. Crank arms 111 and 113 are attached to the driven gears 95 and 97 by bolts 115 and rotate with the associated gears (Fig. 11). The arms 111 and 113 extend outwardly from the center of rotation of gears 95 and 97 in parallel relation and connect to a vertically extending cross arm 117. The cross arm 117 is pivotally supported on the crank arms 111 and 113 by bearing lugs 119 located at points equidistant from the centers of gears 95 and 97. The connecting rod 89 associated with the punch means 31 is fixedly attached to the cross arm 117 and is positioned so that it extends horizontally through the arcuate slot 90 located in the back member 65 of casing 64, the associated can opening bit 85 being vertically disposed (Figs. 10 and 11).

The vertically aligned gears 93, 95 and 97 are all of the same size and shape and accordingly, rotational movement of the gears 95 and 97 maintain the parallel relationship of the associated crank arms 111 and 113 and the vertical disposition of the cross arm 117. As a result of movement of the gears 93, 95, and 97, the con-

necting rod 89 is translated over an arcuate path in slot 90 and, at the same time, the attached bit 85 is maintained in the vertical position.

The slot 90 in the plate 65 is covered by a rotatable metal disc 91 which is centrally supported, in the illustrated construction, upon the plate 65 by pin 91a, an aperture 91b being provided adjacent the outer edge of the disc 91 which fits around the rod 89. Through this arrangement, the movement of the arm 89 is operative to rotate the disc 91 about pin 91a. As a result, the slot 90 is covered at all times preventing access to the power transmission means 35 from the front of the machine 15. It will be apparent to those familiar with the art that other means may be provided for closing slot 90 while at the same time permitting movement of the connecting rod 89.

The power means 33 is operative to drive gear 93 and move the bit 85 through its arcuate path in slot 90. In the illustrated embodiment, the power means 33 is disposed in compartment 63, located in the rearward portion of the housing 29, and comprises an alternating current, series wound motor 121 and a conventional gear reduction unit, designated generally as 123 in the drawings. The motor 121 is of the reversible type and is adapted to operate from a 110 volt, 60 cycle supply or other available source of power. The motor includes the usual armature winding 121a and field coil 121b (Fig. 13). The gear reduction unit 123 links the motor 121 and shaft 107 of the power transmission means 35 so as to rotate the drive gear 93 at about 7½ R. P. M.

The control circuit 37 is both electrical and mechanical in nature and includes a cam and relay arrangement for readying and operating various parts of the vending machine 15 in timed relation and for insuring the safety of persons using the can-opening apparatus 13. In particular, the control circuit 37, shown schematically in Fig. 13, is connected to a source of power by a duplex, conductor cord 124 which terminates in a conventional plug 125. The control circuit 37 includes a single pole, single throw switch 127, a protective fuse 129 and a starting circuit designated generally as 131 (Fig. 13). The starting circuit 131 includes a circuit 133 which is normally closed by a switch actuated by the asepticizing means 36, a starting solenoid 135, a circuit 137 which is opened by insertion of a can 25 into chamber 59, a circuit 139 operatively connected to the coin operated unit 19, a circuit 141 which is operated by the door 55 closing the chamber 59 and safety means 143 for preventing access to the chamber 59 while the can 25 is being punched.

The control circuit 37 further comprises a plurality of cams which are operative to control the movement of the punch means 31 after the motor 121 has been energized by the starting circuit 131 and includes a circuit breaking cam 145, a cam 146 operative to reverse the direction of the motor 121, a circuit interrupting cam 147, and a cam 148 which is operative to reverse the direction of motor 121 thereby to return the punch means 31 to the standby position 43. The cams 145, 146, 147 and 148 operate through associated electrical connections, which will be hereinafter described, to perform the indicated operations. In order to prevent indiscriminate use of the straws 41, means 150 are provided in the control circuit 37 for locking door 81 to the straw compartment 77 when the can opening apparatus 13 is not actuated. In addition, a pair of cir-

cuits 151 and 152 are provided for testing and maintenance purposes.

The cord includes a pair of conductors 153 and 155, one conductor, 153, being grounded to the frame (not shown) of the vending machine 15, the other conductor, 155, being connected to the single pole switch 127. The plug 125 is adapted to fit into a wall socket to provide power for the control circuit 37 and power means 33. The single pole switch 127 is of a commercially available type and connects to the fuse 129 which serves the usual function of protecting the electrical circuit from shorts or overload conditions. Power is conducted from the fuse 129 through the circuit 133 which is normally closed by the asepticizing means 36 to a main power line or bus, designated generally as 157.

The normally closed circuit 133 comprises a switch 159 which is closed by the asepticizing means 36. The switch 159 (Fig. 3) includes a vertically extending flexible arm 163 which is supported at the upper end upon the plate number 65 and a pin 165 which is attached to the lower end of the arm 163 and which extends through an aperture in the plate member 65 into the chamber 61 to engage the asepticizing means 36. In order to assure closure of the switch 159 a blister or boss 167 is located on the inner side of the door 57 to compartment 61 which forces the asepticizing means 36 into positive engagement with the pin 165.

The starting relay 135 may comprise any one of a number of commercially available alternating current type units which comprise a solenoid 169 and an armature 171 including a plunger 173 and means, such as 175 and 177, for alternately closing two independent circuits by electrically connecting contacts 179 or contacts 181. One side of the solenoid 169 is grounded and the other side is connected to circuit closing means 175 through lead 183 so that a self-holding circuit may be provided for the relay 135. When a current is passed through the solenoid 169, the plunger 173 is raised closing contacts 181, as shown in Fig. 13. On the other hand, when the solenoid 169 is not connected to a source of power, the plunger 173 drops, connecting contacts 179 through the circuit closing means 177.

The circuit 137 which is opened by insertion of a can 25 of merchandise into chamber 59 includes a switch 187 of the same type as that described previously in connection with circuit 133 but the switch, in this case, is normally closed, being opened by insertion of can 25. The door 55 to chamber 59 is also provided with a boss (not shown) to hold can 25 in the guide means 71 when the door is lowered thereby positively opening switch 187. The switch 187 is electrically connected to the bus 157 through a conductor 189 and to the starting solenoid 135 through conductors 191 and 193.

The circuit 139 which is operatively connected to the coin operated unit 19 includes a delay or timing relay 195 which is connected to the coin operated unit 19 through conductor 199 and to a suitable source of electric current, such as battery 201. The timing relay 195 may be of any well known type having a solenoid 197, two pairs of contacts, such as 203 and 205, which are alternately closed, and a time delay mechanism which may be adjusted to a predetermined period. In the preferred embodiment, the delay mechanism comprises a dash pot, shown schematically at 207 in Fig. 13 and is adjustable for release periods between the limits of 0 to about 2 minutes. To

operate this circuit, a coin is dropped into slot 23 of the coin operated unit 19 causing a pulse of current to be passed through conductor 199 and the solenoid 197. As a result, the timing relay 195 is operated opening contacts 203 and closing contacts 205. The relay 195 does not restore itself to its normal position until after the predetermined delay period which is preferably about 2 minutes.

The contacts 203 of the timing relay 195 are normally closed and are connected to the bus 157 through conductor 209 and to ground through conductor 211, and contacts 181 and solenoid 169 of the starting relay 135. This provides a self-holding circuit for the starting relay 135 which is broken by energizing the timing relay 195, opening contacts 203.

The door operated circuit 141 is in parallel with the circuit 139 opened by the delay relay 195 and includes a conventional type switch 213 which is opened by raising the door 55 and closed by lowering this door. The switch 213 includes a door engaging cam 215 which slides into an indentation 217 formed in the door 55, when it is lowered, causing switch 213 to close (Fig. 13). The switch 213 is electrically connected to the bus 157 through lead 219 and to ground through conductors 221 and 211, and contacts 181 and solenoid 169 of the starting relay 135. Thus a second self-holding circuit for the starting relay is provided which is broken by opening switch 213.

The safety means 143 for preventing access to compartment 59 by the purchaser includes a generally L-shaped mechanical latching member 223 which is connected to the plunger 173 of the starting relay 135. The latching member 223 is operative to lock the door 55 closed when the plunger 173 drops, to hold the plunger 173 in an intermediate position when door 55 is raised, and to unlock the door 55 when the punching operation is completed.

The latch member 223 includes a pair of legs, which are at right angles to one another, one leg 225 being connected to the plunger 173 by a pin 226, the other leg 227 having a notch 228 formed at its outermost end which is proportioned to engage the top edge of the door 55. In addition, the latch member 223 is pivotally supported upon the housing 29 by a pin 229 and is positioned and proportioned so that the notch 228 engages the top edge of the door 55 when the plunger 173 of the starting relay 135 drops. The leg 227 permits free movement of the door 55 when the plunger 173 is raised, and the latch member 223 is dimensioned to engage the face of the door 55, when raised, to prevent the plunger 173 from dropping below an intermediate position when the door 55 is raised.

In order to drop the plunger 173 of the starting relay 135 to connect contacts 179 and to energize the motor 121, a coin is inserted in the coin operated unit 19. This causes the timing relay 195 to operate to open contacts 203. In addition, the door 55 must be raised to effect the opening of switch 213 to thereby disconnect the two self-holding circuits which energize the starting relay 135.

After the door 55 has been raised, the can 25 of merchandise is inserted into compartment 59. The insertion of the can opens switch 187 and, as a result, the starting relay solenoid 169 is wholly disconnected from the bus 157. The plunger 173 is then electrically free to drop. However, before the plunger can drop, the door

55 must be closed so that the notch 228 of the latch member 223 can move into engagement with the top of the door 55 locking it in the closed position.

5 When the plunger 173 of the starting relay 135 drops, contacts 179 are electrically connected so that current is connected from the bus 157 through conductors 231, 233, and 235, a normally closed switch 237 associated with the circuit breaking cam 145, and the conductor 239 to the armature 121a of the motor 121. The armature 121a is connected to the field coil 121b of the motor 121 through conductor 241, switch 243 and lead 245. In order to complete the motor 15 energizing circuit, the field coil 121b is connected to ground through wire 247 and switch 249.

As a result of the above connection, the motor 121 is started and, as before pointed out, the cams 145, 146, 147, and 148 control the remaining movements of the motor 121. These cams are keyed or otherwise fixedly connected to the shaft 99 associated with the upper gear 35 of the power transmission means 33 so that rotation of the motor 121 causes rotation of the cams. 20 Each of the cams 145, 146, 147 and 148 includes an eccentric portion 251, 252, 253, and 254 respectively, which are operative to actuate associated switches 237, 255, 257 and 259.

The motor 121 is operative to first rotate the 30 shaft 99 and cams 145, 146, 147, and 148 in a clockwise direction (Fig. 13), and at the same time, move the punch means 31 clockwise (Fig. 11) from the standby position 43. After rotating the cams about 175°, the eccentric portion 251 35 of circuit breaking cam 145 opens the associated switch 237 disconnecting the motor 121 from the bus 157. As a result the motor is de-energized but the inertia of the power means 33 and associated parts causes the cams 145, 146, 147, and 148 to continue rotation for at least 5° so that normally open switch 255 is closed by the eccentric portion 252 of the associated cam 146. The closing of switch 255 causes the starting relay 135 to be re-energized, unlocking door 55, and 40 reverses the connections to the field winding 121b of the motor 121 so that the motor will operate in the opposite direction.

45 Switch 255 comprises contacts 261 and 263 and is connected to the bus 157 through conductor 50 265. Contact 261 is connected to the solenoid 169 of the starting relay 135 through conductors 267 and 193, thereby energizing the starting relay 135. As a result, plunger 173 is raised, unlocking latch member 223, and contacts 181 are 55 closed so as to permit self-holding of the relay 135 through the door operated circuit 141 and/or coin operated circuit 139. If the door 55 is raised, the plunger 173 is mechanically held up and removal of can 25 closes switch 187 causing the starting relay 135 to be positively operated.

The other contact 263 of switch 255 connects the bus 157 to a multi-contact, switching relay 60 269 which includes self-holding contacts 271, motor energizing contacts 273, and motor reversing or transfer switches 243 and 249. When the relay 269 is energized by connection to the bus 157, the contacts 271 and 273 are closed and switches 243 and 249 are actuated to reverse the field coil connections of the motor 121.

More particularly, when the field reversing switches 243 and 249 are actuated, the phase of the current passing through the field coil 121b is reversed by connecting the armature winding 121a to the opposite side of the coil 121b through

lead 241, switch 243, and conductors 275 and 247. The other side of the coil 121b is grounded through conductors 245 and 277, and switch 249.

The motor energizing contacts 273 are connected to the bus 157 through a conductor 281 and to the armature winding 121a through conductors 283 and 239. Accordingly, closure of switch 255 by cam 146 energizes the motor 121 and causes it to travel in the opposite direction so that the cams 145, 146, 147, and 148 and punch means 31 are moved in a counter-clockwise direction.

The eccentric portion 252 on cam 146 is positioned so as to close switch 255 at a time prior to termination of clockwise rotation of the cams 145, 146, 147 and 148, but after the motor 121 is de-energized. This is done in order that a safety factor be provided and the apparatus will continue to operate if for some reason the deceleration of the power means 33 be increased, as for example, during cold weather operation, during the first few cycles of the apparatus 13 after a period of non-use, etc.

Self-holding contacts 271 keep the relay 269 energized after switch 255 is opened. This is accomplished by connecting the relay 269 to the bus 157 through conductors 285 and 287, self-holding contacts 271, lead 289, testing means 151, conductor 291, the circuit interrupting switch 257 associated with cam 147, and conductor 293.

After approximately 195° of counter-clockwise rotation of the cams 145, 146, 147, and 148 and bit 85, i. e. about 15° beyond the rest position 43, the eccentric portion 253 of interrupting cam 147 opens switch 257 de-energizing relay 269. As a result, switches 243 and 249 are actuated, reversing the field coil connections of the motor 121 and opening the motor energizing contacts 273. However, the inertia of the power means 33 causes additional counter-clockwise rotation or coasting so that the eccentric portion 254 of cam 148 closes the associated switch 259. As in the case of cam 146, switch 259 is closed while the cams 145, 146, 147, and 148 are coasting so that any sluggishness in the system will not prevent further operation of the apparatus 13.

When switch 259 is closed, the bus 157 is connected to the motor 121 through conductor 295 effecting a clockwise rotation of the cams 145, 146, 147, and 148 (Fig. 13), whereupon the switch 259, after a few degrees of such rotation of the motor 121, is opened disconnecting the motor 121. The inertia of the power means 33 and associated parts carries the cams 145, 146, 147, and 148 and punch means 31 to the rest or standby position 43.

The circuit 150 for opening the straw compartment 77 includes a solenoid 299 having a plunger 301 and associated latch member 303 similar to that which locks the door 55 to compartment 59. The solenoid 299 is connected to the bus 157 through conductor 305, and to ground through contacts 205 of the timing relay 195 and conductor 309. Thus, the solenoid 299 is only energized for the delay time of relay 195. The latch member 303 normally locks the door 81 of the straw compartment 77, however, energization of the solenoid 299 causes the plunger 301 to be lifted thereby moving the associated latch member 303 and unlocking door 81.

The test circuits 151 and 152 include keys 309 and 311 respectively which are operative to actuate various circuits and parts in the can opening apparatus 13. Through reference to Fig. 13, persons familiar with the art can readily

ascertain the operative relationship of these keys to the control circuit 37.

The asepticizing means 36 includes an asepticizing solution 313, a container or receptacle 315, a member 317 which is operative to flush the solution 313 around the bit 85 when entering the container 315 and wipe a substantial portion of the solution from the bit 85 when removed from the container, and a novel frame structure 319 disposed within the container 315 for supporting wiping member 317. In the preferred embodiment of the invention, the asepticizing means 36 further includes a rectifier 323, shown schematically by dotted lines in Fig. 13, which is operative to pass a current through an ionized asepticizing solution 313 and liberate a sterilizing gas on the surface of the bit 85 to more effectively destroy any harmful bacteria.

The receptacle 315 is of a commercially available type and is preferably fabricated from metal. The receptacle 315 includes the usual cylindrical sides 325, top 327 and bottom 329, and is desirably of the same dimensions and type as the can 25 used to contain the merchandise so that a can may be used for either purpose. The top 327 may have lines of weakness 331 formed therein so that a circular portion may be punched out to permit the entry of the bit 85 into the can 315 (Fig. 4). On the other hand, a conventional type can opener may be used to remove a portion of the top 327.

The flushing and wiping member 317 is fabricated from a flexible elastic material, such as rubber, and is generally disc shaped having a diameter somewhat less than the diameter of the can 315. In the illustrated construction, a plurality of radially extending slits or cuts 333 are formed in the flushing and wiping member 317 which extend outwardly from an opening in the center of the member a distance approximating $\frac{1}{2}$ the radius as shown in Fig. 7. As a result, a plurality of generally triangularly shaped flaps 335 are formed.

The novel frame structure 319 of the asepticizing means 36 is fabricated from a pair of identical sections 336 one of which is shown in detail in Fig. 6a. Each section, as shown, comprises a generally horizontally extending annular section 337, having a diameter somewhat less than the diameter of the can 315, a plurality of downwardly extending legs 339 and a multiplicity of upwardly extending arms or tabs 341, the legs 339 and arms 341 being integral with the annular section 337.

In order to assemble the frame structure 319 and support the wiping member 317, a first section 336 is held upright and the wiping member 317 placed on the annular section 337. A second frame section 336 is fitted over the first section so that its annular section 337 fits over the wiping member 317. The two frame sections 336 are held together by bending the arms or tabs 341 of the second frame section 336 under the annular section 337 of the first frame member 336, as shown at 345, thereby positively holding the wiping member 317 between the respective annular sections 337.

The legs 339 press against the sides 325 of the can 315 along their length and engage the bottom 329 of the can 315 at their foot. As a result of the relation between the frame sections 336 certain legs 339 extend below others and, accordingly, these legs are bent, as shown at 340. If a can having very thin metal is used, it will be desirable to bend all of the legs 339 in this

expended to be driven from the can 315 in a rigid manner to prevent puncture of the bottom 329 of the can 315. The unbent arms 341 also press against the sides 325 of the can 315 and engage the top 327 at their upper end. As a result, the frame structure 319 is rigidly held in the can 315.

When the frame member 319 is placed in the can 315, openings 347 are formed between the annular sections 337, wiping member 317 and the sides 325 of the can 315. These openings provide passageways for the asepticizing solution between the space above and that below the wiping member 317. In operation, when the bit 85 enters the asepticizing means 36, the flaps 335 are depressed, flushing solution 313 up through openings 347 around the upper portion of the bit 85 (Fig. 8). When the bit 85 is withdrawn from the solution, the flaps 335 are inverted causing a suction so that solution 313 is rapidly drawn down through openings 347 (Fig. 9). In addition to this suction when the bit is withdrawn, the flaps 335 wipe a substantial portion of the solution 313 from the bit 85.

The sterilizing solution 313 in the can 315 should asepticize and wash the bit 85 when it enters the can 315. Accordingly, the solution preferably comprises a detergent and bactericide which are compatible with one another. By way of example, a mixture of a chlorine compound and an alkali, such as a solution containing 2 parts of sodium hypochlorite, 4.8 parts of tri-sodium phosphate and 95 parts water, has been found to be very satisfactory. The solution ionizes so that it is possible to conduct current therethrough and simultaneously liberate chlorine and provide agitation around the bit 85. However, it should be understood that the ionized solutions may be used independent of electric current for asepticizing the bit.

The liberation of chlorine and agitation of the solution around the bit 85 is accomplished by connecting the punch means 31 to ground, and the rectifier unit 323 to the can through lead 349, and contact 351. The rectifier unit 323 is operated at a negative potential so as to liberate chlorine and cause agitation at the bit 85 of the punch means 31. The rectifier 323 is connected to the power input on the protected side of fuse 129 through lead 353, shown in dotted lines in Fig. 13. Thus, when the bit 85 is introduced into the hypochlorite solution an electrolytic cell is formed, the bit 85 comprising an anode, the can 315 a cathode. A switch 355 is shown in lead 353 for permitting selective operation of the rectifier unit 323.

In the alternative, a non-ionic solution may be used for cleansing and sterilizing the bit 85. As an example, a mixture of a quaternary ammonium compound and a non-ionic detergent, such as a solution containing a .02 part cetyl dimethyl ammonium bromide, 1 part sodium alkyl aryl sulfonate, and 100 parts of water. When a solution of this nature is used it is not necessary to use the rectifier unit 323.

In order to insure sanitary operation, the asepticizing means is frequently changed and this is usually done when the vending machine is replenished.

Now considering the overall operation of the vending machine 15, to prepare the machine for operation, plug 125 should be inserted in a conventional wall socket which supplied 120 volts and 60 cycle current. The switch 127 should then be closed and a can 315 of the asepticizing

solution 313 placed in compartment 61 thereby closing switch 159 and connecting power to the bus 157. If an ionized asepticizing solution is used and rectifier 323 employed switch 355 should also be closed.

In order for a purchaser to obtain an opened can of merchandise, chocolate milk in the present instance, a coin must be inserted in slot 23 causing a can 25 of milk to drop into the dispensing tray 17 and the timing or delay relay 195 to operate. The purchaser must then remove the can 25 from the tray 17, raise the door 55 which is operative to open switch 213, place the can of merchandise in the guides 71 in compartment 59 and close the door 55 thereby opening switch 187. As a result, the starting relay 185 is electrically de-energized and the plunger 173 of the starting relay 185 drops, closing contacts 179 and energizing the motor 121. The timing relay 195 unlocks the door 81 to the straw compartment 77 and the purchaser may obtain a straw 41 within the delay time of relay 195 which is preferably set at about 2 minutes.

In order to more clearly understand the cycle of the punch means 31 and its vertical position throughout the can opening cycle, reference should be made to the diagrams illustrated in Figs. 14 and 15. Referring more particularly to Fig. 14, after the motor 121 is energized, it accelerates along line 361 and rotates at a constant speed as shown by line 363 until the bit 85 punctures the can 25. After the can is punctured, switch 237 is opened to de-energize the motor 121 which continues to coast at a decreasing rate, as shown by dotted line 365.

Before the motor 121 stops, switch 255 is closed causing a very rapid deceleration and normal acceleration of the motor 121 in the opposite direction as shown by lines 367 and 369, respectively. Switch 255 is also operative to unlock the door 55 and permit the purchaser to remove the opened can of merchandise. The opposite rotation continues until the bit 85 of the punch means 31 enters the asepticizing solution 313 in can 315 whereupon switch 257 is opened and the motor coasts as shown by dotted lines 371.

As the bit enters the asepticizing solution 313 an electrolytic cell is formed conducting a current between the sides of the can 325 and the bit 85 causing chlorine gas to be liberated around the bit and local agitation of the solution when the described hypochlorite solution is used.

Before bit 85 has coasted to a stop in the solution, switch 259 is closed and the motor rapidly decelerates to zero velocity and accelerates in the opposite or original direction, as shown by lines 373 and 375 in Fig. 14. Shortly thereafter, switch 259 is opened thereby disconnecting the power to the motor 121. The motor then coasts to the rest position 43 as shown by the dotted line 377 and the can opening apparatus is ready for re-use. The height of the bit at various times in the can opening cycle is illustrated in Fig. 15.

A modified punch means 319 is shown in Fig. 16, and when this is used an opening 380 is provided for consuming the contents of the can and a vent hole 380a is formed (Fig. 17). The modified punch means 319 comprises a connecting arm 381 which connects to the cross bar 117 of the power transmission means 35 at one end and at the other end connects to a crosspiece 383. The crosspiece 383 provides support for a vertically extending spike 385 and a bit 387 which is in parallel relation with the spike 385. The spike pro-

vides the vent hole 380a and consequently is somewhat smaller than the bit 387.

Various of the features of this invention which are believed to be new are set forth in the following claims.

We claim:

1. In apparatus for opening a can of merchandise, a receptacle containing a sterilizing liquid, a can opening punch, actuating means for piercing said can with said punch and for thereafter contacting said punch with said liquid.

2. In apparatus for opening a can of merchandise, a receptacle containing a sterilizing solution, a can opening punch, actuating means for piercing said can with said punch, for contacting said punch with said solution, and for thereafter effecting relative movement of said punch and receptacle to free said punch from said solution.

3. In can opening apparatus of the type described, a receptacle containing a sterilizing solution, a punch member normally positioned out of said solution, operating means for moving said punch member from its normal position into engagement with a can of merchandise, puncturing the can of merchandise, reciprocally operating said punch into said solution and thereafter restoring said punch member to its normal position for subsequent use.

4. In apparatus for opening cans of merchandise, an ionized sterilizing solution, a can opening member, and means for alternately operatively engaging said can opening member with a can of merchandise and with the solution, and means for conducting an electrical current through said punch and said solution when said opening member is in the solution.

5. In can opening apparatus of the type described, a receptacle containing an ionized sterilizing solution, gas forming ions in said solution, a punch, means for alternately operatively engaging said punch with a can of merchandise and with said solution, and means for applying an electrical potential between said can and said punch when the punch is in said solution, said electrical means being polarized to liberate gas at said punch.

6. In combination, a can piercing punch and means for sterilizing said punch comprising a receptacle having a top and bottom and containing a sterilizing liquid and a wiping member positioned intermediate the top and bottom of said receptacle, said member comprising a sheet of

flexible elastic material having an opening and a plurality of slits formed therein, said slits extending outwardly from said opening, means for reciprocating said punch through said member into and out of said sterilizing liquid at about said opening in said sheet so as to wipe said punch as an incident to said reciprocating movement.

7. A device for sterilizing a can-opener, comprising in combination a receptacle which contains a sterilizing liquid, said receptacle including a bottom and top, said top having an opening formed therein to permit entry and withdrawal of a can-opener, a frame disposed within said receptacle, said frame comprising a pair of frame sections, each frame section including a generally horizontally extending annular section, a plurality of leg members which extend vertically between the annular sections and bottom of the receptacle, and a multiplicity of arms integral with said annular section, said frame sections being arranged so that the respective annular sections are in spaced parallel relationship, and being interconnected by a portion of said arms, the remainder of said arms extending vertically and engaging the top of said receptacle, and a wiping member which is held between said spaced annular sections, said member including a sheet of elastic material having a plurality of slits formed therein which extend from a common point on said sheet, said member being operative to wipe said can-opener in its passage therethrough.

ROY A. BRUCE.
